DESIGN FOR A TOOTH BRUSH

George Leslie Herrick, Westfield, N. J., Joseph P. Hardie, Hartsdale, and Arthur Cobb, Jr., Bronxville, N. Y., assignors to Bristol-Myers Company, New York, N. Y., a corporation of Delaware

Application September 29, 1937, Serial No. 71,862

Term of patent 14 years

To all whom it may concern:

Be it known that we, George Leslie Herrick, Joseph P. Hardie, and Arthur Cobb, Jr., citizens of the United States, residing at Westfield, county of Union, State of New Jersey; Hartsdale, county of Westchester, State of New York; and Bronxville, county of Westchester, State of New York, respectively, have invented a new, original, and ornamental Design for a Toothbrush, of which the following is a specification, reference being had to the accompanying drawing, forming a part thereof, in which:

Figure 1 is a perspective view taken from the

front of a toothbrush embodying our new design.

Figure 2 is an end view of the brush as seen from the right end of Figure 1, and

Figure 3 is a perspective view of the toothbrush as seen from the back.

We claim:

The ornamental design for a toothbrush as shown.
